ELECTRONIC LABORATORY WORK CENTER

Arthur W. Carlson, Muskegon, Mich., assignor to E. H.
Sheldon & Company, Muskegon, Mich., a corporation
of Michigan

Filed May 2, 1966, Ser. No. 2,082

Term of patent 14 years

(Cl. D16—2)

FIG. 2

FIG. 1 is a perspective view of an electronic laboratory work center showing my new design, the opposite side of the work center being identical with that shown in the drawing; and

FIG. 2 is a top plan view thereof, with portions fragmentarily shown for clarity of illustration.

I claim:

The ornamental design for an electronic laboratory work center, as shown and described.
